UNITED STATES PATENT OFFICE.

HARRY W. HILL, OF CLEVELAND, OHIO.

DESIGN FOR A FRAME OR SUPPORT FOR FRICTION-CLUTCHES.

SPECIFICATION forming part of Design No. 18,443, dated July 10, 1888.

Application filed April 9, 1888. Serial No. 210,139. Term of patent 14 years.

To all whom it may concern:

Be it known that I, HARRY W. HILL, a citizen of the United States, residing at Cleveland, in the county of Cuyahoga and State of Ohio, have invented and produced a new, useful, and original Design for a Frame for Friction-Clutches, of which the following is a full, clear, and exact description, reference being had to the accompanying drawings, in which—

10 Figure 1 is a perspective view thereof, and Fig. 2 is a sectional view on line $\alpha\alpha$.

15 My invention relates to friction-clutches; and it consists in the design which comprises a central hub and six arms radiating therefrom at intervals of about sixty degrees.

In the drawings, A represents the frame, α the hub thereof, and α' the arms, of which there are six, which radiate from said hub at

intervals of about sixty degrees; and α^2 represents ribs raised along both edges of each arm and on both the back and front sides thereof.

20 This form of clutch-frame is symmetrical and pleasing to the eye without giving to the design the appearance of clumsiness.

I claim—

25 The design for the frame or support of a friction-clutch herein shown and described, which consists of a hub and six supporting-arms radiating therefrom at intervals of about sixty degrees, each arm having ribs raised 30 along both edges on each and on both sides thereof.

HARRY W. HILL.
